EX

DESIGN FOR A BADGE.

Design No. 12,545, dated October 25, 1881.

UNITED STATES PATENT OFFICE.

GUSTAV MUNDER, OF BALTIMORE, MARYLAND.

DESIGN FOR A BADGE.

SPECIFICATION forming part of Design No. 12,545, dated October 25, 1881.
Application filed September 28, 1881. Term of patent 3½ years.

To all whom it may concern:

Be it known that I, GUSTAV MUNDER, of Baltimore, in the county of Baltimore and State of Maryland, have invented a Design for Badges, of which the following is a specification.

My invention consists in a badge of novel design, especially intended for use during the festival held in the city of Baltimore, Maryland, known as the "Oriole," and to be preserved as a memento of that occasion.

The badge consists of a medal suspended from a pin or clasp, the medal bearing on one face the representation of a flying bird—the oriole—either with or without the word "oriole," and with or without the date, which latter would, of course, be changed from year to year, if new medals are struck off; and the other face bearing a representation of the "Battle Monument," of Baltimore, with or without the words "Baltimore Festival." By preference the medal is suspended by a ring or link from the talons of a flying oriole of sheet metal provided

with a pin by which to attach it to the clothing; but the manner of attaching the medal to the pin is not important, though the design of the pin constitutes a feature of my invention. In other words, the essential features of my invention are a pin or clasp made in representation of a flying oriole and a medal suspended therefrom and bearing on one face a representation of a flying bird and on the other face a representation of a monument.

Having thus described my invention, I claim—

The herein described design for a badge, consisting of a pin or clasp in imitation of a flying bird, and a medal suspended therefrom, having on one face the figure of the oriole bird, and on its other face a representation of a monument.

GUSTAV MUNDER.
